UNITED STATES PATENT OFFICE

153,752

DESIGN FOR A FONT OF SIGN LETTERS OR SIMILAR ARTICLE

Joseph E. Baker, Newark, Ohio

Application March 6, 1947, Serial No. 137,393

Term of patent 3½ years

(Cl. D64—12)

To all whom it may concern:

Be it known that I, Joseph E. Baker, a citizen of the United States, residing at Newark, in the county of Licking and State of Ohio, have invented a new, original, and ornamental Design for a Font of Sign Letters or Similar Article, of which the following is a specification, reference being had to the accompanying drawing, forming a part thereof.

Fig. 1 illustrates face views of a font of sign letters, showing my new design;

Fig. 2 is a perspective view of one of the letters for showing a third dimension which is typical of all of the letters;

Fig. 3 is a perspective view of the numerals of the font of sign letters; and

Fig. 4 is an edge elevational view of one of the numerals for the purpose of showing a third dimension.

I claim:

The ornamental design for a font of sign letters or similar article, substantially as shown and described.

JOSEPH E. BAKER.
